UNITED STATES PATENT OFFICE.

JAMES B. JARMIN, OF OSCEOLA, NEBRASKA, ASSIGNOR, BY MESNE ASSIGNMENTS, TO THE IMPLEMENT MANUFACTURING COMPANY, OF DAVENPORT, IOWA.

WINDMILL.

SPECIFICATION forming part of Letters Patent No. 662,939, dated December 4, 1900.

Application filed November 18, 1899. Serial No. 737,508. (No model.)

To all whom it may concern:

Be it known that I, JAMES B. JARMIN, a citizen of the United States, residing at Osceola, in the county of Polk and State of Nebraska, have invented certain new and useful Improvements in Windmills, of which the following is a specification.

This invention relates to improvements in that class of windmills known as "direct-acting," in which the wheel-shaft directly actuates the pump-rod as contradistinguished from that class in which transmitting-gearing is interposed between the shaft and rod—as, for instance, the rim and bevel cog-wheels now commonly employed.

The difficulty with direct-acting mills as heretofore constructed arises from the great friction and binding developed and the jerky pounding stroke imparted to the pump-rod, which not only reduces the efficiency of the mill, especially in light winds, but injuriously affects the parts as well as the operation of the pump, rendering the mill practically useless for many purposes.

This invention has for its objects the obviation of all these difficulties and the production of a mill that shall be smooth, certain, and easy of operation under all conditions, that shall be strong, cheap, and durable in construction, that requires the minimum power to operate it, and that shall be easily and readily thrown into and out of operation without the expenditure of any considerable force or the employment of complicated or expensive mechanism. These and such other objects as may hereinafter appear are attained by the devices illustrated in the accompanying drawings, in which—

Figure 1 represents a side elevation of a windmill embodying my invention, the wheel being shown in section. Fig. 2 represents a vertical sectional view, taken on the line 2 2 of Fig. 1, looking in the direction indicated by the arrows. Fig. 3 is an enlarged detail view of the operating mechanism for the pump-rod, which latter is omitted. Fig. 4 is a horizontal sectional view, taken on the line 4 4 of Fig. 1, looking in the direction indicated by the arrows; and Fig. 5 is a detail section of the mast.

Similar letters of reference denote the same parts in the several figures of the drawings.

Referring by letter to the accompanying drawings, A indicates the tower, which may be of any suitable construction, that shown 55 in the drawings being an ordinary wooden tower provided with the usual metallic cap B, bolted or otherwise secured thereto and constituting the upper bearing for the mast C, which may be supported at its lower end 60 in any well-known or convenient manner. Upon the upper end of the mast is secured the masthead D, having its upper portion offset and provided with a horizontal bearing E, in which loosely works a short shaft F, having 65 mounted upon one end thereof the wheel G, which may be of any ordinary or desired construction, the wheel being keyed upon or otherwise rigidly secured to the shaft. Upon the opposite end of the shaft is rigidly 70 mounted an eccentric H, on which rides a roller I, held in place by and loosely journaled in a bar J, pivoted at its opposite end to an arm K, extending substantially horizontally from one side of the masthead, said 75 bar constituting a guide and keeper for the roller in its vertical movements induced by the cam or eccentric upon the wheel-shaft. The journal or pivot L of the roller I is prolonged to receive the upper end of the pump-rod M, which passes freely down through the lower portion of the masthead and through the mast to the pump, (not shown,) with which 80 it is connected in the usual or any desired manner. Thus it will be seen that when the 85 wheel is "in the wind" its rotation will cause a corresponding rotation of the shaft thereof carrying the eccentric H, and as the latter rotates it causes a vertical reciprocation of the roller I with the minimum friction, and 90 such motion is imparted to the pump-rod, which works with a smooth steady motion without jerks or pounding in the strongest winds, and even in the lightest breezes the same motion will be imparted to the pump- 95 rod, as the operating mechanism thereof is of such character as to respond promptly to and with the least resistance to the action of the wheel and requires but little power for its operation. It will be observed that the 100

length of the guide-bar J and its disposition are such that the journal of the roller I passes through a short arc of such radius that it reciprocates practically on a straight line and 5 does not tend to produce an appreciable binding, springing, or friction nor require slotted parts to permit of lost motion in order to avoid these difficulties.

From the side of the masthead opposite 10 the wheel extends a pair of ears N, affording pivots for the vane O, and to one arm (preferably the lower one) of the vane surrounding the pivot thereof is rigidly secured a bevel-gear P, meshing with a corresponding 15 bevel-gear Q, loosely journaled upon a stud R, projecting from the side of the masthead in proper position to receive the gear. Cast with or otherwise rigidly secured to the gear Q is a segment S, which is preferably provided with sprocket-teeth on its periphery to receive the links of a sprocket-chain T, one 20 end of which is secured to the segment and the other end of which is secured to an ear or other suitable projection U on a ring V, 25 loosely mounted upon a sleeve W and confined against longitudinal movement thereon by any suitable means, such as by an annular shoulder on one end of said sleeve and a collar X, rigidly secured to the sleeve. The 30 sleeve W is slidably mounted upon the mast C immediately below the masthead—that is, it is free to slide longitudinally on the mast, but is prevented from rotating thereon by a spline-and-feather connection with the mast 35 or by any other suitable device ordinarily employed for this purpose. To the sleeve is secured the upper end of a pull-rod Y, the lower end of which extends down within convenient reach from the ground, so that when 40 the rod is pulled it will draw down the sleeve and, through the intermediary of the chain T and segment S, cause a partial rotation of the bevel-gears P and Q, thus forcibly swinging the vane O to a plane substantially parallel 45 with the wheel G, thus resulting in causing the edge of the wheel to be presented to the wind and allowing the wheel to come to a rest, as usual in devices of this class. To the bevel-gear Q is connected in any suitable 50 manner, such as by the arms E, a counter-weight a, which will of course be raised when the gear is partially rotated to throw the mill out of operation, as above described, and when the pull-rod is released the counter-weight serves to materially assist the swinging 55 of the vane back to its position at right angles to the wheel, thus throwing the mill "in wind" to operative position. In point of fact in practice the usual result of pulling 60 on the rod Y to throw the mill out of operation is to swing the wheel around at right angles to the vane instead of swinging the vane, which is usually held to its position by the wind; but at any rate the parts are 65 caused to assume their different positions by

the mechanism above described. It is of course necessary in such operations that the point of attachment of the chain T to the sleeve W shall swing around the axis of the mast with the relative movements of the mast-head and vane, and to this end I provide a slotted bar rigidly secured at one end to the masthead and projecting downwardly past the sleeve to receive a pin or bolt e, rigidly secured to the ring V, to which the chain is 70 attached, both passing freely through the slot in the bar, so as to permit of the raising and lowering of the sleeve in the shifting operation.

These devices are exceedingly simple, cheap, 80 and durable in construction, are prompt and easy of operation, and produce the desired result as effectually, if not more so, than any of the prior and complicated devices for this purpose known to me.

Having described my invention, what I claim, and desire to secure by Letters Patent, is—

1. In a windmill, the combination with a mast, a masthead and a vane pivoted to said masthead, of a gear connection between said masthead and vane, a sleeve upon the mast, a connection between said sleeve and the gear on the masthead for rotating the same, and a rod for operating and controlling the movement of said sleeve manually, whereby the relative angular positions of said vane and the masthead may be adjustably regulated and held positively in such adjusted positions, 90 substantially as described.

2. In a windmill, the combination with a mast, a masthead and a vane pivoted to said head, of a gear connection between said vane and head, a segment attached to the gear on the masthead, a sleeve upon the mast and movable longitudinally thereof, a chain attached at its ends, respectively, to said sleeve and the segment for imparting movement to said gear connection, and a rod for actuating and manually controlling the movement of the sleeve whereby the relative angular positions of said vane and the masthead may be adjustably regulated and held positively in such adjusted positions, substantially as described.

3. In a windmill, the combination with a mast, a masthead and the vane pivoted to the masthead, of a gear connection between said vane and masthead, a segment upon the mast-head-gear, a counterweight attached to said gear, a sleeve slidably, but non-rotatively, mounted upon the mast, a ring loosely mounted on said sleeve, a chain connecting said ring and segment, said ring being connected, so as to rotate, with the masthead, and a rod 120 for actuating said sleeve, substantially as described.

4. In a windmill, the combination with a mast, a masthead and the vane pivoted to the masthead, of a gear connection between said

vane and masthead, a segment upon the mast-head-gear, a counterweight attached to said gear, a sleeve slidingly, but non-rotatively, mounted upon the mast, a ring loosely mounted upon said sleeve, a chain connecting said ring and segment, a slotted bar rigidly secured at one end to the masthead, a bolt rigidly se-

cured to said ring and working freely in the slot in said bar, and a rod for actuating the sleeve, substantially as described.
